UNITED STATES PATENT OFFICE.

ERNEST H. KORSMAYER, OF EVANSVILLE, INDIANA.

SEED-PLANTER.

SPECIFICATION forming part of Letters Patent No. 351,926, dated November 2, 1886.

Application filed July 27, 1886. Serial No. 209,228. (No model.)

To all whom it may concern:

Be it known that I, ERNEST H. KORSMAYER, of Evansville, in the county of Vanderburg, in the State of Indiana, have invented a new 5 and Improved Seed-Planter, of which the following is a full, clear, and exact description.

Reference is to be had to the accompanying drawings, forming a part of this specification, in which similar letters of reference indicate 10 corresponding parts in all the figures.

Figure 1 is a broken side elevation, partly in section, of my improved seed-planter. Fig. 2 is a transverse sectional elevation taken on the line $x-x$ of Fig. 1. Fig. 3 is a sectional 15 plan view of the cutter and seed-dropping tube, taken on the line $y-y$ of Fig. 1; and Fig. 4 is a plan view of a double machine, designed for planting two rows at a time.

The invention consists of the construction, 20 arrangement, and combination of parts, all as hereinafter described and claimed.

A represents the axle to which the drive-wheels B C are secured. Upon the axle are placed the flanged collars D D', to which the 25 side bars, E E, of the main frame of the seed-planter are attached. Rising from the side bars, E E, are the handles F, by which the planter is held and guided by the operator. The collar D' is placed upon the axle A, next 30 to the inner end of the hub of the wheel C, while the collar D is placed upon the axle next to the outer end of the hub of the wheel B, the axle being extended through the hub of wheel B for that purpose. Placed loosely upon the 35 axle, between the collar D' and the wheel B, are the two concaved hollow castings G H, which form the seed-box, each casting being formed with a tube, G' H', which fits upon the axle, and the ends of these tubes meet at or 40 near the center of the axle. The casting G is formed upon its outer surface, near the wheel B, with the lugs a a, by which it may be locked to the wheel B by a dog or lever, I, to cause the casting to revolve upon the axle with the 45 wheel B, to effect the dropping of the seed. The edge of the casting G is formed with the flange b, through which is formed numerous seed-dropping apertures, c c. The casting H is formed at its edge with the flange d, which 50 is of larger diameter than the flange b of casting G, and when the castings are put together

upon the axle A the flange d laps past the flange b, as shown in Fig. 2, leaving a small space between. In this space is fitted a wooden ring, J, made in sections, and the sections of this ring are constantly pressed in contact with the outer surface of the flange b by the action of numerous small coiled springs, e, fitted in small recesses formed in the outer surface of the sections, and acting against the flange d. 55 A seed-dropping space, f, is formed in the wooden ring J and flange d, for the seed to drop from the seed-apertures c into the spout K, which conducts the seed to the opening cut in the ground by the knife or opener L. The 60 knife L is a broad curved knife, made as a part of or attached to the tube K, and both are attached to the lower portion of the casting H by being bolted or riveted to the flange M, cast upon or secured to the flange d of said casting. 65 The casting H being loose upon the axle A and carrying the knife, it is necessary to lock the casting in order that the knife may penetrate the ground and open a furrow. This I accomplish by means of lugs g, cast upon the 70 surface of the castings H, with which lugs the sliding lever N engages. The lever N is held in guides attached to the main frame and one handle, F, and is controlled by a small handle, f', and a spring, f'', and I form a series of the 75 lugs, g, upon the casting H, so that the casting may be held to cause the knife to enter the ground more or less, as desired. By withdrawing the rod N from engagement with lugs g the casting H may be turned back upon the 80 axle to entirely clear the knife L from the ground, which is necessary in taking the planter from place to place.

In the tube K is fitted a valve, O, for temporarily retaining the seed dropped into the tube. 90 This valve is normally held closed by the spring o acting upon the stem of the valve. The cord o', leading from the valve to the small lever O', pivoted to the handle F, is to enable the plowman to conveniently open the valve and hold it open, or permit it to close to prevent the dropping of seed.

The dog or lever I above mentioned for throwing the planter in and out of gear is pivoted upon a stud, i, formed upon the hub of 95 the drive-wheel B. This lever is formed at one end with a prong, i', which passes through

an orifice in the web or one of the spokes of the wheel. When the lever is in the position shown in full lines in Fig. 2, the prong i' engages with one or the other of the lugs a on the casting G and causes the casting to revolve with the wheel. When the lever is turned to the position shown in dotted line in Fig. 2, the casting G is disengaged from the wheel and remains relatively stationary. For turning the lever I upon its pivot, I form one end of the lever with the curved block i , the other with a similar block, i' , and provide the right-hand side of the machine with the sliding rod P , which is arranged so that when shovied down its lower end will be in position to be struck by the curved blocks i i' . If the lever I is in position so that the prong i' engages with one of the lugs a and the rod P be forced downward, the curved block i will strike the rod P and turn the lever I on its pivot to nearly a vertical position and move the prong i' out of the range of the lug a , and then throw the planter out of gear. In order to put the planter again in gear, the rod P must be forced downward again in time to be struck by the curved block i' , which will cause that end of the lever I to be forced inward a sufficient distance to cause the prong i' to engage one or the other of the lugs a . When in gear, the casting G revolves with the wheel B , and carries the seed in suitable quantity in the seed-apertures c , up to the opening f , through which the seed drops into the spout K , and is conducted thereby to the ground.

In order to avoid danger of the apertures c carrying too much seed to the opening f , I provide a brush, Q , arranged to sweep the inner surface of the flange b . This brush is attached to a block, R , attached to the inner surface of the casting H by the plate R' , which rests upon a spring seat or cushion, S , preferably of soft rubber. This cushion gives the block R a yielding action, so there will be no grinding of the seed between it and the inner surface of the flange b of the casting G . In the block R is also fitted a spring-plunger having a rounded head, h , which drops into the seed-apertures c as they successively come in line with the plunger and forces the seed out of the apertures at the proper time, so there can be no clogging of seed in said apertures and no failure of the planter to drop the seed regularly.

The seed is introduced to the seed-box through a door, h' , made in the casting H , and in order to adapt the machine to plant hills greater or less distance apart, I provide the

casting G with the sliding plates j , arranged to close the seed-apertures c , and by properly handling the valves the hills may be made at any desired distance apart, thus adapting the machine both for drilling and planting.

In Fig. 4 I have illustrated a duplex machine for planting or drilling two rows at a time. This consists simply of two of the machines complete, as shown in the other figures of the drawings, united together by a suitable frame, consisting in this instance of the main-frame bar T , the two rectangular frames T T' , surrounding the planters, and the cross-pieces T T' , uniting the rectangular frames. A slat-seat may be arranged upon the cross-pieces T T' for the planter, if desired.

Having thus fully described my invention, what I claim as new, and desire to secure by Letters Patent, is—

1. In a seed-planter, the hollow casting G , formed with a single flange, b , having numerous seed-apertures, c , formed in it, the casting H , forming one side of the seed-box and formed with a single opposite flange, d , overlapping the flange b , in combination with the ring J , placed between the flanges b and d , substantially as described.

2. The ring J , held between the flanges b d of the hollow castings G H , and pressed inward by the springs e , substantially as described.

3. The hollow casting G , having a flange provided with seed-apertures, in combination with the hollow casting H , provided upon the inside with a block, R , held upon a spring-support, substantially as described.

4. The hollow casting G , having an apertured flange, b , in combination with the casting H , cushion S , plate R' , and block R , substantially as described.

5. The casting G , provided with the lugs a , and placed loosely upon the axle, in combination with the wheel B , dog or lever I , and means, substantially as described, for operating the dog or lever I for engaging and disengaging the lugs a , substantially as and for the purposes set forth.

6. The casting H , placed loosely upon the axle formed with the lugs g , and provided with the knife L , in combination with a locking-rod for locking the casting, to cause the knife to enter the ground, substantially as described.

ERNEST H. KORSMEYER.
